UNITED STATES PATENT OFFICE.

JOHN W. SHANER, OF WILLIAMSPORT, PENNSYLVANIA, ASSIGNOR TO THE NATIONAL BISCUIT COMPANY, OF CHICAGO, ILLINOIS.

WRAPPER-PASTING DEVICE.

SPECIFICATION forming part of Letters Patent No. 682,817, dated September 17, 1901.

Application filed December 3, 1900. Serial No. 38,429. (No model.)

To all whom it may concern:

Be it known that I, JOHN W. SHANER, of Williamsport, county of Lycoming, and State of Pennsylvania, have invented certain new and useful Improvements in Wrapper-Pasting Devices, of which the following is a specification.

My invention relates generally to devices for facilitating the wrapping of packages, and 10 has reference more particularly to and has been designed more especially for use in connection with the application of the outer wrapping or label to boxes or packages of rectangular shape containing manufactured food 15 products.

The manufacture and sale of prepared food-stuffs—such, for instance, as bakery and cereal products—put up in sealed packages of uniform sizes and shapes suitable for the retail trade has grown to enormous proportions. In the packaging of such goods an outside wrapper in the nature of a label containing the names of the contained article and its manufacturer, with printed directions for use, 20 is commonly applied by hand to the package, the under side of its outer longitudinal fold receiving a strip of paste and its two ends being neatly folded flat and commonly having end seals applied thereto.

30 My invention has for its principal object or function to facilitate the application of this outer wrapper or label to such packages; and it relates more specifically to a simple and convenient device for applying paste in even 35 quantities and over a uniform surface area of any desired width.

My invention in its preferred form is illustrated in the accompanying drawings, in which—

40 Figure 1 is a plan view, and Fig. 2 is a side elevation.

Referring to the drawings in detail, A represents a suitable base-plate, preferably of rectangular shape and of a size adapted to the requirements of the particular size of wrappers 45 employed in connection therewith. Secured in or to the upper face of this base-plate parallel with and a short distance from one end of the same is a horizontally-disposed bar or strip B of a length equal to the width of the base-plate. This bar B is designed to serve as

a stop or abutment for the upper end of a bundle of wrappers or labels C, which is laid flat on the base-plate, as shown, and substantially the upper half thereof may be narrowed, 55 as at b, for a purpose hereinafter disclosed.

D designates a paste-guard in the form of a pivoted rectangular bail, the principal member d of which consists of a single straight strip formed of sheet metal or any other suitable material, slightly convexed on its outer surface and having its straight lower edge adapted to lie upon the upper sheet of the wrappers C transversely of the same. To the ends of the strip d are secured a pair of 60 arms e of considerable length, which extend rearwardly and are pivoted at their other ends to a pair of adjustable plates E, set in the opposite sides of the base-plate A and adjustably secured therein by means of 65 a slot f and a set-screw g. Through the base-plate A and at any suitable and convenient distance apart are formed a pair of vertical slots F, designed to accommodate a pair of horizontally-adjustable stops G. The stops 70 G may each conveniently consist simply of a metal casting comprising a horizontal foot member h and a vertically-disposed member i, which latter is designed to serve as an abutment for the lower end of the pile of 75 wrappers C and to be of a sufficient height to also serve as a stop or abutment for the box or package which is to be wrapped. The stop G is adjustably secured in any desired position along the slot F by means of a headed 80 screw k, passing through said slot from beneath and through the horizontal member h of the stop and engaging a wing-nut l at its upper screw-threaded end.

K designates a suitable paste holder or receptacle, which may be conveniently located at the upper end of the device, being secured and held in position by means of an extended clip L, which fits over the upper narrowed edge of the transverse bar B.

9 The operation of the device is as follows: When a package, as M, is to be wrapped, a stack of wrappers C, somewhat less in height than the height of the stops G, is laid upon the base-plate A so that their upper or front edges closely abut the transverse bar B, as shown in Fig. 2. That done, the adjustable

stops G are moved up into engagement with the lower or rear edges of the wrappers and secured in such position. The box or package M is then placed on top of the wrappers 5 in a position indicated by dotted lines. By means of the brush P the operator applies a strip of paste to that portion of the top wrapper lying between the lower edge of the guard d and the opposite wall of the bar B by simply drawing the brush across the space or passage thus formed. By reason of the convex character of the face of the guard d the lower longitudinal margin or edge portion of said guard rests squarely upon the upper 15 surface of the wrappers in a plane substantially vertical thereto, thus sharply defining the inner edge of the paste-strip, while the upper longitudinal portion of the guard retreats from the brush of the operator, thus obviating danger of paste from the brush working over the upper edge of the guard and dripping down the inner or under face thereof. The operator then raises the inner or lower end of the top wrapper, passing it over the nearer face of the box M and folding it over the top of the latter. The box is then drawn backward until it abuts the stops G, as shown in full lines, Fig. 2. This action withdraws the pasted end of the wrapper from beneath the guard d, which latter at the same time removes any surplus and unnecessary paste that may have been deposited on the wrapper. The pasted end of the wrapper is then folded up over the farther side of the package, and its marginal fold is lapped over the opposite end of the wrapper previously folded on top of the box. The ends of the wrapper are then neatly folded, so as to lie flat and parallel with the end surfaces of the box and are secured by the application of end seals or, where preferred, by a cord or equivalent device passed entirely around the package. The package is then removed, and the device is ready for a similar operation upon the next package.

From the foregoing description it will be seen that my invention provides for an expeditious, even, and uniform application of paste to the surface of the wrapper through strip the width of which may be easily regulated by means of the adjustable plates E in the sides of the base-plate A, to which the arms of the paste-guard are pivoted. It will also be noticed that the simple act of withdrawing the upper end of the wrapper from beneath the lower edge of the guard automatically removes any surplus of paste beyond what is necessary to secure the opposite ends of the wrapper together above the package. The cutting away or narrowing of the upper portion of the transverse bar B affords additional room for the operation of the brush applying the paste. The clip L performs a double function of securing the paste-box in a convenient and accessible position and the same time serving as a guard for the removal of surplus paste from the brush before

applying the latter to the wrapper, in which operation one or both sides of the brush are drawn transversely across the upper edge of the clip, the paste thus removed from the brush dripping down the inner surface of the adjacent wall of the box into the body of paste contained therein.

When it is desired to clean the paste-guard, 75 or when the pile of wrappers has been exhausted and is to be replaced by a new set, the bail D may be swung back out of the way through a half-circle for either of the purposes specified.

80 The base A may be a simple rectangular or other shaped plate, as shown, adapted to rest upon a table, counter, or other support, or it may obviously be provided with suitable legs or other support and in itself constitute 85 a table.

I claim—

1. In a device of the character described, the combination with a base-plate and a transverse bar or partition secured thereon near 90 one end and forming a stop or abutment for a stack of wrappers, of a paste-guard pivoted to the sides of the base-plate and adapted to swing into and out of operative position adjacent said transverse abutment, substantially as described.

2. In a device of the character described, the combination with a base-plate and a transverse bar or partition secured thereon near one end and forming a stop or abutment for 100 a stack of wrappers, of a paste-guard adjustably pivoted to the sides of the base-plate and adapted to swing into and out of operative position adjacent and parallel with said transverse abutment, substantially as de- 105 scribed.

3. In a device of the character described, the combination with a base-plate and a transverse bar or partition secured thereon near 110 one end and forming a stop or abutment for a stack of wrappers, of a paste-guard in the form of a rectangular bail, having its two arms pivoted in the sides of the base-plate and its transverse guard member arranged adjacent and parallel with the vertical face 115 of the transverse abutment, and normally resting with its lower edge across the topmost wrapper near one end thereof, substantially as described.

4. In a device of the character described, 120 the combination with a base-plate and a transverse bar or partition secured thereon near one end and forming a stop or abutment for a stack of wrappers, of a paste-guard in the form of a rectangular bail, having its two 125 arms pivoted in the sides of the base-plate, and its transverse guard member arranged adjacent and parallel with the opposing vertical face of the transverse abutment and normally resting with its lower edge across the 130 topmost wrapper near one end thereof, the operative face of said guard member being slightly convexed, substantially as described.

5. In a device of the character described,

the combination with a base-plate and a trans-
verse bar or partition secured thereon near
one end and forming a stop or abutment for
a stack of wrappers, of a paste-guard pivoted
5 to the sides of the base-plate and adapted to
swing into and out of operative position ad-
jacent said transverse abutment, and a stop
in said base-plate adapted to engage the lower
end of the stack of wrappers, substantially
10 as described.

6. In a device of the character described,
the combination with a base-plate and a trans-
verse bar or partition secured thereon near
one end and forming a stop or abutment for
15 a stack of wrappers, of a paste-guard pivoted
to the sides of the base-plate and adapted to
swing into and out of operative position ad-
jacent said transverse abutment, and a series
of horizontally-adjustable stops in said base-

plate adapted to engage the lower end of a 20
stack of wrappers, substantially as described.

7. In a device of the character described,
the combination with a base-plate and a trans-
verse bar or partition secured thereon near
one end and forming a stop or abutment for 25
a stack of wrappers, of a paste-guard pivoted
to the sides of the base-plate, and adapted to
swing into and out of operative position ad-
jacent said transverse abutment, a horizon-
tally-adjustable stop in said base-plate adapt- 30
ed to engage the lower end of the stack of
wrappers, and a suitable paste-holder secured
to said transverse bar or partition, substan-
tially as described.

JOHN W. SHANER.
